SLEEPING BAG

Bestor Robinson, United States Army,
Oakland, Calif.

Application May 9, 1942, Serial No. 442,304

2 Claims. (Cl. 5—343)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

This invention relates to certain new and useful improvements in sleeping bags and more particularly to that type of bag known as a mummy sleeping bag.

The primary object of the invention is to provide a sleeping bag composed of a single blank of material, cut, folded and stitched together to form a complete sleeping bag and hood section for the body and head of the occupant.

This bag has been constructed in this manner in order that the bag may turn with the sleeper, since all previously-known bags of this type have been constructed so that the sleeper turns inside of the bag. This bag, therefore, makes for a more comfortable as well as a warmer bag with less weight, a very important item to the soldier or camper, since it is so designed that very little additional weight is added to the shoulder pack.

With the above and other objects and advantages in view, the invention consists of the novel form, combination and arrangement of parts hereinafter more fully described, shown in the accompanying drawings and claims.

In the drawings, wherein like reference characters designate corresponding parts throughout the several views,

Fig. 1 is a top plan view of the single blank form from which the sleeping bag is constructed.

Fig. 2 is a top plan view of the completed sleeping bag.

Fig. 3 is a top plan view of the completed sleeping bag in use.

Fig. 4 is a side elevational view of the sleeping bag in use, and

Fig. 5 is a perspective view of the sleeping bag rolled ready for transportation.

Referring more in detail to the accompanying drawings, 10 is the blank from which the sleeping bag is constructed, the blank embodying a body portion 11 and a head section 12, formed by notches 13 and 14, to provide fold-over portions 16 and 17 respectively in the form of triangular extensions from the body portion at approximately the shoulder line and a central triangular extension notched at 15 to form two smaller triangular extensions for correctly forming the hood section when the blank is folded and completed as shown in Fig. 2. Semi-circular openings 18 are formed in the head section 12 to form complete circular opening 19 for the face of the occupant. The blank 11 is so stitched around its en-

tire perimeter, except where the halves of the interlocking fastener 20 are attached, that the bag encompasses the occupant in a like manner as a mummy is encased. The usual cam slide 21 is provided to join the interlocking elements of the fastener 20 together when the bag is occupied and such an arrangement also permits the occupant to open the upper portion of the bag to facilitate getting into and out of the bag or for turning it inside out for airing.

Fastening means 22 are provided on the lower end of the body portion 11 for retaining the bag in folded position, as shown in Fig. 5. Pull strings 23 are attached to the base of the head section 12 in order that the bag can more readily be adapted to conform to the head of the occupant.

Referring more particularly to the method in which the blank is folded to form the bag as shown in Fig. 2, the meeting edges 24 of the body portion are stitched together by stitching as referred to above and the meeting edges 25 are stitched together to form a seam 26 in the center of the bag, on its upper surface. In a like manner the edges 26, 27, 28 and 29 are also stitched together, forming the circular opening 19 which is bound by a tape 30 to prevent fraying of the material during use. The bag thus completed will conform to the shape of the occupant and when occupied will turn to either side, depending on the occupant.

It is believed from the above description that those skilled in the art will clearly understand the construction of the sleeping bag without going into a more detailed or lengthy statement with regard to the merits and construction of the bag but it is to be understood that this disclosure is merely illustrative and that such changes in the invention may be made as are fairly within the scope and spirit of the following claims.

Having thus described the invention, what is claimed as new and desired to secure by Letters Patent is:

1. A blank for a sleeping bag comprising a sheet having a wide, saw-toothed top and a narrower straight bottom, the sides being substantially parallel for approximately one-third of the distance downwardly from the top and converging for their remaining length, said top edge including two triangular projections having their outer edges formed as a continuation of the side edges of the sheet and a larger central triangular projection having a notched extremity, and the outer edges of each of said two projections having a curved notch, said triangular projections being adapted

to form a tapered head portion having a face opening when their edges are joined.

2. A sleeping bag comprising an elongated mummy-shaped envelope formed of a sheet of material having two opposite edges joined for a portion of their length to form a front center seam and having the bottom closed by a continuation of the front center seam, said bag having a face opening formed by notches in the said two edges of the sheet and a closable opening below the face 10

opening for access to the interior of the envelope, the head portion of the envelope having four seams for shaping it to the head and shoulders of the wearer, two of said seams extending from the top of the head portion diagonally to each side of the envelope, one extending down the front to the face opening and one extending from the top a short distance down the back of the head portion.

BESTOR ROBINSON.
